UNITED STATES PATENT OFFICE.

JAMES S. COPELAND, OF HARTFORD, CONNECTICUT, ASSIGNOR TO THE
POPE MANUFACTURING COMPANY, OF SAME PLACE AND PORTLAND,
MAINE.

VELOCIPED.

SPECIFICATION forming part of Letters Patent No. 558,260, dated April 14, 1896.

Application filed May 13, 1895. Serial No. 549,463. (No model.)

To all whom it may concern:

Be it known that I, JAMES S. COPELAND, a citizen of the United States, and a resident of the city and county of Hartford, State of Connecticut, have invented certain new and useful Improvements in Velocipedes, &c., of which the following is a specification, reference being had to the accompanying drawings, forming a part hereof.

10 This invention relates to means for connecting together different parts of the frames of velocipedes, or other frames or parts of any other structure, of which one at least is tubular.

15 I have herein illustrated the invention as applied for the special purpose of connecting together the upper and lower rear-fork tubes of bicycles and for supporting the rear axles, whereby the position of the rear axle may be 20 adjusted according to the variations in the length of the driving-chain; but it will be understood that the invention is not limited to such use.

25 The features of improvement wherein the invention consists will be fully described hereinafter, and will be pointed out in the claims which follow.

In the accompanying drawings, which form a part hereof and in which I have represented 30 embodiments of my invention, Figure 1 is a side view of the rear portion of the frame of a bicycle to which my improvements are applied, parts being represented as broken away in order to save space in the drawings. Fig. 35 2 represents in edge view a connection-piece and two half-thimbles, hereinafter referred to, ready for assembling. Fig. 3 is a face view of the connection-piece shown in Fig. 2. Fig. 4 is a face view of a connection-piece or toe-piece 40 adapted to be secured to one of the upper rear-fork tubes and to receive and support the rear axle. Fig. 5 is a face view of a connection-piece adapted to be secured to one of the lower rear-fork tubes for connection 45 with the toe-piece shown in Fig. 4. Fig. 6 is an edge view of the toe-piece and connection-piece shown in Figs. 4 and 5, fastened together as indicated in Fig. 1.

The means of connection which is herein 50 referred to has been devised with particular reference to its use with such parts of a bi-

cycle-frame as are directly concerned with the adjustment of the rear axle for variations in the length of the driving-chain; but by reason of its cheapness and the large amount of 55 brazing-surface allowed, which gives great strength for the amount of metal, it is equally useful in other parts of the frame, in frames other than bicycle-frames, and in fact in any structure in which a tubular part is to be connected to a flat or flattened part or piece, and I will therefore proceed to describe it generally without reference to the particular use.

As shown in Figs. 1, 2, and 3, the connection-piece A is formed of sheet metal and is 60 of a width which adapts it to fit within the end of the tube, as B, to which it may be applied. Near its inner end it is preferably provided with one or more marginal notches a a. With the connection-piece is combined 65 a thimble, or, as represented, two half-thimbles C C', which are adapted to fit snugly within the end of the tube, as B, and to embrace between them the connection-piece A, the two parts preferably having lugs c c to 70 engage the corresponding notches a a in the connection-piece.

When the parts are assembled, they are 75 brazed together and are also brazed within the end of the tube. The notches a a and the corresponding lugs may be dispensed with, but are preferably employed. As represented 80 in Figs. 2 and 3 and in the upper portion of Fig. 1, the connection-piece A is shown as having a hole a' for the reception of a bolt, by 85 which it may be pivotally connected with the seat-post bracket in order to permit each upper rear-fork tube to swing as its lower end is adjusted.

It is obvious that the connection-piece may 90 have any suitable form, according to its location and use, the means for securing it to the tube being substantially the same in all cases. Thus the connection-piece D (shown in Fig. 4 and at the lower end of Fig. 1) is adapted 95 for the reception of the axle of the rear wheel and for coöperation with the connection-piece E. (Shown in Fig. 5 and also at the lower end of Fig. 1.) As the part of the frame which usually supports the axle of the 100 rear wheel is commonly called the "toe-piece," this part D will be so designated here-

inafter in order to distinguish it from the other connection-pieces referred to.

It will be observed that the connection-piece or toe-piece D has a slot or fork d for

- 5 the reception of the axle of the rear wheel.
- 10 The upper rear-fork tubes being adapted to swing and means being provided for effecting the desired adjustment of such upper rear-fork tubes and for retaining said tubes firmly
- 15 in adjusted position, it will be obvious not only that the required adjustment may be effected readily and quickly, but that the rear wheel may be removed from its bearings whenever necessary, without taking the drive-chain apart or altering the adjustment of either frame or chain. The connection-piece E, having a shank e by which it is secured to the lower rear-fork tube, is provided with a slot e' , which is disposed transversely with respect
- 20 to the axis of the upper rear-fork tube B. The toe-piece D has a hole d' for the reception of a bolt H, which passes through the slot e' of the connection-piece E and receives a washer h and nut h' , whereby the two pieces
- 25 D E may be clamped firmly together in the required position. The connection-piece E has also a hole e^2 , in which is secured, by brazing or otherwise, a stud I, which receives the adjusting-screw K, the latter being adapted
- 30 to bear against the toe-piece D and thereby to effect the required adjustment of the upper rear-fork tube.

It will be obvious that other arrangements of the parts may be made, if desired, and that

- 35 other clamping and adjusting means may be substituted for those shown.

The advantages of the improved means of connection in the way of cheapness, lightness, and strength, in whatever structure it may be employed, will be clearly apparent. 40

It will be understood that I do not intend to limit my invention to the exact construction and arrangement herein shown and described, nor, with respect to the means of connection, to any particular use. 45

What I claim, and desire to secure by Letters Patent, is—

1. The combination with a tube, of a flat connection-piece adapted to be inserted within the end of said tube and having in its edges 50 one or more notches and a thimble adapted to be inserted with the connection-piece in said tube and to be secured therein and having one or more lugs to engage the corresponding notches in the connection-piece, substantially as shown and described. 55

2. The combination with a tube, of a flat connection-piece adapted to be inserted within the end of said tube and having in its edges one or more notches and two half-thimbles 60 adapted to embrace the end of said connection-piece between them and to be inserted therewith and secured in said tube and having one or more lugs to engage the corresponding notches in the connection-piece, substantially as shown and described. 65

This specification signed and witnessed this 10th day of May, A. D. 1895.

JAMES S. COPELAND.

In presence of—

WILLIAM T. HAMILTON,
HELEN L. DAY.
